X-RAY CATHODE SHIELD

Nelson H. Stewart, Verona, N. J., assignor to
Westinghouse Lamp Company, a Corporation
of Pennsylvania

Application December 1, 1931. Serial No. 578,243

7 Claims. (Cl. 250—35)

This invention relates to electrical discharge devices and more particularly to devices of this character employed for the production of X-rays and commonly termed X-ray tubes. In its more specific aspect the invention is directed towards the prevention of undesirable electrical discharges and especially those occurring or having a high tendency to occur at the edges of the X-ray screen supporting and shock absorbing spring members directed towards the anode.

Since the period of Roentgen's discovery, X-ray tubes of variable designs and sizes have been rather extensively employed in sundry and different fields. One type of X-ray tube design which I shall employ merely as an illustration so that the benefits of my invention may be made clearly apparent is that described in U. S. Patent 1,715,152 granted to C. T. Ulrey et al. on May 28, 1929 and that described in the patent application of A. C. Blakeman, Serial No. 560,738, filed Sept. 2, 1931 and assigned to the same assignee as the present invention.

The X-ray tube generally comprises a cylindrical envelope having one of its ends of bulbous or hemispherical contour and having at its other end a reentrant tube whose diameter is substantially less than the corresponding dimension of the envelope. Along about the middle third length of the envelope is a second reentrant tube, with one of its ends fusedly secured to the envelope. Disposed above the free end of said second reentrant tube is a suspended metallic screen, housing a cathode and having its outer surface spaced from the inner wall of the envelope. The inner end of the first mentioned reentrant tube has firmly sealed thereto a metallic sleeve adapted to support an anode. The anode, being of such lengthwise and cross sectional dimensions that its loaded free end is spaced from and within the inner side walls of the metallic screen, has its outer wall or a substantial portion thereof surrounded by and spaced from the inner wall of the second reentrant tube.

In United States Patent 1,715,152 hereinbefore identified, the physical characteristics of an X-ray tube of this design were enhanced by providing supporting and shock absorbing means for the anode and cathode screen. As shown therein the anode and the cathode are surrounded by and secured to slotted resilient collars or sleeves respectively bearing against the second reentrant tube and the envelope. The resilient frictional bearing portions of these sleeves are relatively thin and are of the order of about .020 inch in thickness. Blakeman in

his application heretofore identified discloses an improvement over the Ulrey resilient members and substitutes therefor a plurality of spaced resilient plates of about the same order of thickness as the resilient bearing portions of the Ulrey cylindrical spring sleeves.

It sometimes has been found that when a voltage is applied between the anode and the cathode that an electrical discharge takes place between the anode and the edges of the resilient supporting and shock absorbing means, surrounding the screen and facing said anode. This may be in the nature of a corona effect around these edges of said resilient means or a spark over therebetween and the anode.

This invention has been devised to eliminate or at least greatly minimize this obviously undesirable effect and briefly stated comprises providing a means for shielding the edges of the resilient supporting and shock absorbing means from the anode.

An object of my invention is to provide means for the elimination of some of the undesirable electrical discharges in electrical discharge devices.

Another object of my invention is to provide an X-ray tube of rugged mechanical and electrical design.

Another object of my invention is to provide means for the elimination of electrical discharges at the edges of the screen supporting and shock absorbing members of an X-ray tube.

Fig. 1 represents a fragmentary view with some of the parts shown in elevation and others in section of an X-ray tube embodying my invention.

Fig. 2 represents a cross sectional view taken on line II—II of Fig. 1 in the direction of the arrows.

Fig. 3 represents a modification of Fig. 1.

Fig. 4 represents a cross sectional view taken on line IV—IV of Fig. 3 in the direction of the arrows.

Although I shall hereinafter describe my invention as applied to an X-ray tube of the general type disclosed in the Ulrey et al. patent and the Blakeman application hereinbefore identified, I do not mean to be limited thereby, but merely employ these constructions as convenient means of illustration. Moreover, since the lower end of an X-ray tube embodying a reentrant tube with an anode supporting and shock absorbing means is not essential to the illustration of my invention, I shall describe but the

upper portion of an X-ray tube embodying my invention.

In both Figs. 1 and 3 there is illustrated the upper portion of an X-ray tube, embodying my invention, which comprises a gas tight envelope 10 consisting of a body portion 11 and a hemispherical or bulbous upper end 12. At the upper end of the body portion 11 and in close proximity of the hemispherical portion 12 is a nickel-iron screen 13 housing a cathode (not shown) and the target end of an anode 14 and adapted to screen out undesirable X-rays. The cathode is supplied with electrical current by means of a plurality of conductors hermetically sealed to the envelope 10, one of which is shown as at 15. Besides serving as electrical conducting means, these conductors 15 act to support the metallic screen 13.

So that the tube may be able to withstand shocks without danger of breaking during the normal commercial manipulations, transportation and operation, there are provided resilient means between the outer surface of the screen 13 and the inner wall of the envelope 10 all shown by both Ulrey et al. and Blakeman.

As illustrated the specific resilient means are of the general type disclosed by Blakeman and consist essentially of plates 16 of a flat or slightly marginally curved contour. Each plate is made of a thin resilient molybdenum measuring about .012 inch in thickness. Spaced along the approximate longitudinal center line of each plate are a plurality of punched nipples 18, and extending from the upper edge of each plate is an ear 19 having suitably sized openings therethrough. The screen 13 has a plurality of spaced depressions 21 adapted to receive the nipples 18 of the plates 16, and the upper end of the envelope above the screen has a plurality of nipples 22 on the inner surface thereof adapted to fit in the opening of the ears 19.

As shown the plates 16 are mounted between the outer surface of the metallic screen 13 and the inner surface of the envelope 10. The nipples on the plates and envelope fit snugly in the depressions 21 and the openings 19 respectively with the plates 16 flexed inwardly towards the metallic screen and having a major portion thereof bearing against the inner wall of the envelope and the edges of the marginal portions thereof bearing against the metallic screen 13.

When a sufficiently high voltage is applied between the electrode terminals of a tube of this construction, it was observed that there sometimes occurred an electrical discharge at the end 24 of the resilient means 16 facing the anode.

This electrical discharge manifested itself in the nature of a corona effect around these edges and sometimes in the nature of a spark over between these edges and the anode or the anode supporting sleeve (not shown).

These phenomena if they persisted oftentimes causes an electrical charge to build up on some portion of the glass which eventually causes a rupture thereof.

According to my invention, in order to avoid or to at least materially minimize these liabilities, I provide an inexpensive means which may be readily assembled with the screen and which functions in the nature of a shield to decrease the potential gradient at the edge of the resilient plates to minimize the tendency of an electrical discharge occurring at these edges. This

shielding means may be of any suitable design and as shown in Fig. 1 it comprises a split ring 25 of a resilient refractory material such as resilient molybdenum or the like measuring about .006 inch in thickness. The screen 13 has a circumferential slot or recess 26 of appropriate dimensions in the outer surface thereof so that the ring 25 may be readily mounted thereon with the outer surface of the lower edge thereof being positioned inwardly of the outer surface of the screen 13 or preferably flush therewith.

The ring 25 when mounted consists essentially of a cylindrical lower portion 27 having integrally therewith an upwardly and outwardly extending curved shoulder 28 of a relatively large radius as compared to the lower edges of the plate 16 and a slotted cylinder 29 integral with the upper edge of said shoulder and extending upwardly therefrom. This ring 25 may be readily manufactured by merely stamping a rectangular blank of molybdenum of appropriate dimensions to provide an offset portion 27, a curved shoulder 28 integral therewith and a slotted portion 29 integral with and extending from one edge of the shoulder.

Thereafter the ring 25 may be assembled with the screen 13 to protect the edges of the plates 16 by wrapping the ring around the screen 13, with the offset portion 27 of the ring located within the circumferential slot or recess 26, with the shoulder 28 curved around the edges of the plates 16 and the slotted upper portion 29 encircling and bearing against the lower portion of the plates 16.

The ring 25 is secured to the screen 13 by spot welding or by means of appropriate pins or screws through the offset portion 27 thereof and the screen 13. In a construction of this character, it is apparent that the edges of the plates 16 are shielded from the anode and that the slotted portion 29 of the ring 25 bears against the outer surface of the lower portions of the plates 16 and the inner wall of the envelope 10 to aid in supporting the screen 13 and in distributing and absorbing any shocks on the envelope.

A modification of my invention as shown in Fig. 1 is that illustrated in Fig. 3. As shown in Fig. 3 an alternative means that may be employed as a shielding means for the lower edges of the plates 16 may comprise a split spring ring 30 of resilient molybdenum measuring about .006 inch in thickness or any other suitable material of appropriate thickness. The screen 13 has a circumferential slot 31 on the outer surface thereof, located below the edges of the plates 16 and adapted to accommodate a portion of the split spring ring 30. This split spring ring 30 may comprise a generally cylindrical portion 32 having an outwardly curved shoulder 33 integral therewith and of a relatively greater radius than that of the lower edges of the plates 16, and an inwardly directed flange 34 integral with the shoulder 33 and approximately normal to the cylindrical portion 32.

A small portion of one extremity of the split spring ring 30 is offset slightly inwardly as at 35 so that upon assembly with the screen 13 the other extremity thereof will lie over and in said offset portion. This split spring ring 30 may be mounted in the same general manner as split spring ring 25, with the cylindrical portion 32 encircling the lower portion of the plates 16, 150

the shoulder 33 curved around the edges of the plates 16 and the flange 34 extending into the circumferential recess or slot 31.

In order to assure a rugged flexible assembly 5 and to eliminate the necessity of welding or the use of pins, there is provided a split wire ring 36 of appropriate dimensions which is located in the slot 31 and bears against the upper edge of the slot 31 and against the upper surface of 10 the flange 34.

This split spring ring 30 may be readily mounted on the screen 13 by first placing the wire ring 36 in the circumferential slot 31. Thereafter the split spring ring 30 is placed 15 therearound with the flange 34 located in the slot 31 and abutting against the lower limit of this slot and the wire ring 36 and having its ends overlapping as at 35. The cylindrical portion 32 thereof bears against the outer surface 20 of the lower portions of the plates 16 and when assembled with the envelope this cylindrical portion 32 bears against both the outer surface of the plates 16 and the inner surface of the wall of the envelope 10. In a construction of 25 this character it is apparent that like the construction in Fig. 1, the edges of the plates 16 are shielded from the anode and the cylindrical portion 32 of the shield aids in supporting the screen 13 and in distributing and absorbing any 30 shocks on the envelope.

Although my invention has been described in minute particularity, it is not to be confined to the exact structure shown or described, but is to be limited only by the prior art.

35 What is claimed is:

1. An X-ray tube including an envelope with a cathode, an anode and a screen therein, relatively thin supporting means bearing against the outer surface of said screen and against the inner wall of the envelope, and means associated with said screen and shielding from said anode one edge of said supporting means facing said anode to lower the potential gradient at the edge of said supporting means facing said anode.

45 2. An X-ray tube including an envelope with a cathode, an anode and a screen therein, said screen housing the cathode, relatively thin resilient supporting means bearing against the outer surface of the screen and the inner surface 50 of the envelope and means on said screen shielding the lower edge of said supporting means from the anode, said means having a portion thereof whose radius of curvature is greater than that of said lower edge.

55 3. An X-ray tube including an envelope with a cathode, an anode, and a screen therein, said screen housing said cathode, relatively thin supporting means bearing against the outer surface

of the screen and against the inner surface of the envelope, one of the edges of said supporting means facing the anode and a split ring located between said screen and the envelope, with a portion thereof shielding said edge from 80 the anode.

4. An X-ray tube including an envelope with a cathode, an anode, and a screen therein, said screen housing the cathode, relatively thin supporting means bearing against the outer surface thereof and the inner wall of the envelope, one of the edges of said supporting means facing the anode, a slot in the lower portion of the screen adjacent said edge, and a shield surrounding the said edge and having a portion thereof located in said slot.

5. An X-ray tube including an envelope with a cathode, an anode and a screen therein, said screen housing the cathode, relatively thin supporting means bearing against the outer surface thereof and the inner wall of the envelope, one of the edges of said supporting means facing the anode, a slot in the lower portion of said screen adjacent said edge, and a split ring having a portion thereof bearing against the outer surface of said supporting means and shielding said edge from the anode and another portion located in 90 said slot.

6. An X-ray tube including an envelope with a cathode, an anode and a screen therein, said screen housing the cathode, relatively thin supporting means bearing against the outer surface thereof and against the inner wall of said envelope, one of the edges of said supporting means facing the anode, a slot in the lower portion 105 of said screen adjacent said edge, and means having a portion thereof bearing against the outer surface of the lower portion of said supporting means and shielding said lower edge from the anode and having another portion 110 thereof located in said slot.

7. An X-ray tube including an envelope with a cathode, an anode and a screen therein, said screen housing the cathode, relatively thin supporting means bearing against the outer surface thereof and against the inner surface of said envelope, one of the edges of said supporting means facing the anode, a slot in the lower portion of the screen adjacent said edge and means surrounding the lower portion of said 120 supporting means, said last named means having a curved portion surrounding said edge, the radius of curvature of said curved portion being greater than that of said edge, said last named means having a portion thereof located in said 125 slot.
